Jas. Wager, of Troy, N.Y.
Letters Patent No. 736. Dated Oct. 16th, 1855.

The schedule referred to in the letters Patent, and making part of the same.

To all whom it may concern:

Be it known that I, James Wager, of Troy, in the county of Rensselaer, and state of New York, have invented or produced a new and original design for a book stove, which I call the "Victor", and I do hereby declare that the following is a full, clear, and exact description of the same, reference being had to the accompanying perspective drawing, and to the letters of reference marked thereon making a part of this specification.

My design of book stove is as follows. viz.:
A, is the top plate with the wave moulding border (2), around it.
B is the jamb plate, with the oven door C, C', and fire door D; the oven doors are decorated with ornamental corners (3), and moulding (C). E and E' are ornaments placed upon their panels, the fire door is ornamented upon its panel with the shell work (6). F is the front plate, with the front doors G, G' ornamented upon their panels, with the ornamental and shell work H, H. I is the hearth plate, with the decorated border moulding (C). J is the bottom

plate, with ornamental moulding (J). It is the leg, decorated with shells (g, h) and scroll (i).

Having fully described my design of Cook Stove, what I claim as new and desire to secure by Letters Patent is the ornamental design and configuration of Cook Stove plates, such as herein described and represented in the annexed drawing.
